UNITED STATES PATENT OFFICE.

AUGUST SILBERT, OF FORT STANTON, NEW MEXICO.

CHAIR-BACK.

1,210,223.

Specification of Letters Patent. Patented Dec. 26, 1916.

Application filed July 3, 1914. Serial No. 848,879.

To all whom it may concern:

Be it known that I, AUGUST SILBERT, a citizen of the United States, residing at Fort Stanton, in the county of Lincoln and State 5 of New Mexico, have invented new and useful Improvements in Chair-Backs, of which the following is a specification.

The primary purpose of this invention is the provision of a rest or support for the 10 back of a person when in a sitting position, said back conforming to the configuration of the human back when in a sitting posture so that ease and comfort may result and respiration be full and natural without any 15 tendency to limit the action of the lungs or respiratory organs.

Specifically considered, the invention consists of a back support for chairs and analogous articles for supporting persons in sitting postures, such back having its face 20 shaped to conform to the hollow of the human back and to receive the shoulder blades, whereby the lungs may expand and the person sit erect with the shoulders thrown 25 well back.

The invention consists of the novel features, details of construction and combination of parts, which hereinafter will be more particularly set forth, illustrated and 30 claimed.

In the drawings hereto attached:—Figure 1 is a perspective view of a chair provided with a back embodying the invention. Fig. 2 is an edge view of the chair back. Fig. 3 35 is a top view.

Corresponding and like parts are referred to in the following description, and indicated in all the views of the drawings, by the same reference characters.

40 The numeral 1 designates a support or rest for the back of a person when sitting, and for the sake of simplicity and to avoid confusion, such support will be designated hereinafter as a chair back, although in practice 45 it is not restricted in its application to chairs and may be applied to settees and other articles of furniture generally utilized for receiving a person when sitting.

The face or side of the chair back de-

signed to come in contact with the back of 50 the person is formed with a forward bulge 2, and recesses 3. The forward bulge 2 extends transversely of the chair back and is of such outline as to conform to the hollow of the human back. The recesses 3 are located at 55 the upper corners of the chair back upon opposite sides of a medial line so as to come opposite the shoulder blades of the person when sitting, thereby enabling the shoulders to be thrown backward to admit of the lungs 60 and respiratory organs being fully expanded when indulging in deep breathing.

It is to be understood that the chair back may be of any construction so long as its 65 face presents the forward bulge 2 and the upper side recesses 3.

From the foregoing description, taken in connection with the accompanying drawings, the advantages of the construction and of the method of operation will be readily 70 apparent to those skilled in the art to which the invention appertains, and while I have described the principle of operation of the invention, together with the device which I now consider to be the best embodiment 75 thereof, I desire to have it understood that the device shown is merely illustrative, and that such changes may be made when desired as are within the scope of the invention as claimed.

Having thus described the invention, what 80 is claimed as new is:—

A chair back comprising a substantially perpendicularly disposed single piece of material bent transversely adjacent its base to 85 provide a bulged portion on the front side thereof, the upper end of the back being relatively wider than the remainder of the material and recessed upon the opposite sides of the longitudinal medial portion of the 90 back, the confronting edges of the recesses being reversely curved in the form of an arc.

In testimony whereof I affix my signature in presence of two witnesses.

AUGUST SILBERT.
